United States Patent Office

Des. 205,762
Patented Sept. 20, 1966

205,762

VEHICLE

Robert E. Gerber, Marion, Ohio, assignor to Huber-Warco Company, Marion, Ohio, a corporation of Ohio

Filed June 30, 1964, Ser. No. 80,652

Term of patent 14 years

(Cl. D14—3)

Fig. 2

Fig. 3

FIG. 1 is a side elevational view of a vehicle, the side opposite being substantially similar in appearance;

FIG. 2 is a rear view;

FIG. 3 is a rear perspective view, the upper portion of the cab front being a windshield.

The dominant features of the design reside in the portions shown in full lines.

I claim:

The ornamental design for a vehicle, as shown and described.
